Patented Mar. 6, 1917.

UNITED STATES PATENT OFFICE.

LELAND E. GLENN, OF GREENSBORO, NORTH CAROLINA.

AUTOMATIC SPEED-CONTROLLER FOR RAILWAY-TRAINS.

1,218,395.

Specification of Letters Patent.

Patented Mar. 6, 1917.

Application filed April 22, 1916. Serial No. 92,883.

To all whom it may concern:

Be it known that I, LELAND E. GLENN, a citizen of the United States, and a resident of Greensboro, in the county of Guilford 5 and State of North Carolina, have invented a certain new and useful Improvement in Automatic Speed-Controllers for Railway-Trains, of which the following is a specification.

10 My present invention relates generally to speed controllers, and more particularly to an automatic speed controller for railway trains, my object being to provide a simple inexpensive arrangement whereby trains may

15 be prevented from proceeding beyond the prescribed speed limits and whereby the speed may be cut down outside and beyond the control of the engineer.

20 A further object is to provide an automatic arrangement independent of the manual control of the speed of the train, for securing partial application of the brakes should the speed increase beyond the prescribed limits or predetermined points.

25 In carrying out these objects, I preferably provide the construction and arrangement of parts to be now described with reference to the accompanying drawing, forming a part of this specification, and where- 30 in—

Figure 1 is an elevation, partly broken away and in section, and more or less diagrammatic, of the parts proposed by my invention.

35 Fig. 2 is a view partly in elevation and partly in section, illustrating the rotating parts carried by one of the wheel axles of the train.

Fig. 3 is a detail section taken substantially on line 3—3 of Fig. 2.

Referring now to these figures, I have shown in Fig. 1 at 10, the usual train pipe forming part of the air brake system as well known, and I provide the train pipe with a

45 laterally projecting nipple 11 leading to an opening within a valve casing 12, having an opening in its upper wall and a valve seat surrounding such opening upwardly against which is seated a controlling valve 13 which, 50 upon downward movement away from its seat, dumps the train pipe 10, thus reducing the pressure slightly therein, so as to secure a partial application of the brakes.

55 The lower portion of the stem 14 of the controlling valve 13, disposed within the valve casing 12, is provided with a rigid

set collar 15, and between this collar and the base of the valve casing is a coiled spring 16 by which the valve 13 is normally held in its uppermost position against its seat and in 60 closed position. Upon the upper external portion of the stem 14 is adjustably threaded a stop 17 forming part of a plug 18, the upper free end of which is slidable within the axial bore at the lower end of a head 19, 65 a spring 20 being coiled around the plug 18 between the stop 17 and the lower end of the head 19 whereby to thrust upwardly against the latter, for a purpose to be hereinafter described. 70

Mounted at its lower end in vertical rotatable relation in connection with the central bearing 21 of a supporting bracket 22, is the body 23 of a governor having upper angular arms 25 and having a lower rigid 75 gear 25. The movable weighted governor arms 26 are intermediately pivoted at 27, to the ends of the arms 24, and have their inner ends extended within the upper apertured head 28 of a rod 29 depending through an 80 axial bore of the body 23 of the governor, and the lower reduced end 30 of which rod is extended within a bore axially of the upper end of the head 19 before referred to, whereby rotation of the governor may continue without causing rotation of the head 19 and the valve and its stem before described, and at the same time permits downward longitudinal movement of the governor rod 29 to open the valve 13 when the governor arms 26 swing outwardly and upwardly under effect of the increased centrifugal motion. 90

In engagement with the gear 25 before mentioned is a second gear 31, secured upon the upper end of a stem 32 rotatable in a bearing 33 in the supporting bracket 22 adjacent the bearing 21 before described, the lower end of the stem 32 being connected to a flexible shaft 34 which leads to one of the car axles, such as seen at 35 in Fig. 2, the adjacent end of the flexible shaft 34 being there connected to a shaft 36 as seen in Fig. 3, having secured thereon a worm wheel 37, shaft 36 being mounted in bearings 38 at opposite sides of a casing 39 housing the worm wheel 37, a worm 40 on the portion of the axle 35 upon which the worm 40 is secured, this worm being preferably formed in sections so as to be capable 100 of ready disposition upon an axle 35 and clamped by clamping bolts 41. 105

Thus, rotation of the car axle 35 is communicated through the worm 40 and worm wheel 37, as well as its shaft 36, to the flexible shaft 34, and on to the gear wheel 31, which meshes with the gear wheel 25 and thus rotates the governor at a speed proportionate to that of the axle 35.

The head 19 has a limited movement with respect to the plug 18 at the opposite end of stem 14, and the governor rod is thus permitted a limited movement without opening the valve 13. Upon movement of the governor rod beyond this limit, however, valve 13 is depressed and opens against the tension of its controlling spring 16 and thus vents the train pipe 10. It is obvious the tension of spring 16 may be controlled by adjusting the stop 15 upon the valve stem 14, and thus control or regulate the points in the speed of the train at which the application of the brakes will be effected.

It is further obvious that I provide a simple, convenient means beyond and outside of the control of the engineer, whereby the speed of the train may be positively regulated within limits and the brakes applied to effect a reduction of speed whenever attempt is made to travel beyond the prescribed or safety limits.

30 I claim:—

1. In a train speed regulating apparatus, the combination with a train pipe having a vent, of a valve casing having an upper opening and a valve seat therein around the opening, a connection establishing communication between the interior of said casing and the vent of the train pipe, a valve within the casing seated upwardly against the said seat, a stem upon which the valve is secured having a portion depending within the valve casing and provided with an adjustable stop, a controlling spring coiled around the stem between the base of the casing and the said stop, a plug threaded upon and adjustable on the upper external portion of the valve stem, a head having a lower axial bore into which the upper end of the plug is movable, a spring coiled about the plug and bearing upwardly against the said head, a supporting bracket having adjacent bearings, a governor including a body disposed vertically and having its lower end mounted in one of the bearings of the said bracket and provided with an axial bore, a governor rod movable vertically in the bore and having a reduced lower end disposed in the upper axial bore of the said head, said governor rod having an upper apertured end and said governor also including governor arms intermediately fulcrumed upon the body and having their inner free ends disposed within the aperture of the said rod, a gear wheel secured upon the governor body, a flexible shaft secured at one end to the said gear stem, and gearing connecting the opposite end of the flexible shaft with one of the axles of the train whereby to transmit rotation thereof to the governor, said gearing including a worm secured upon the axle, a worm wheel in engagement with the worm, and a shaft upon which the worm wheel is mounted, connected to the respective end of the flexible shaft.

cured upon the stem and in engagement with the gear wheel of the governor body, a flexible shaft secured at one end to the said gear stem, and gearing connecting the opposite end of the flexible shaft with one of the axles 70 of the train whereby to transmit rotation thereof to the governor.

2. In a train speed regulating apparatus, the combination with a train pipe having a vent, of a valve casing having an upper 75 opening and a valve seat therein around the opening, a connection establishing communication between the interior of said casing and the vent of the train pipe, a valve within the casing seated upwardly against the 80 said seat, a stem upon which the valve is secured having a portion depending within the valve casing and provided with an adjustable stop, a controlling spring coiled around the stem between the base of the casing and 85 the said stop, a plug threaded upon and adjustable on the upper external portion of the valve stem, a head having a lower axial bore into which the upper end of the plug is 90 movable, a spring coiled about the plug and bearing upwardly against the said head, a supporting bracket having adjacent bearings, a governor including a body disposed vertically and having its lower end mounted in one of the bearings of the said bracket 95 and provided with an axial bore, a governor rod movable vertically in the bore and having a reduced lower end disposed in the upper axial bore of the said head, said governor rod having an upper apertured end 100 and said governor also including governor arms intermediately fulcrumed upon the body and having their inner free ends disposed within the aperture of the said rod, a gear wheel secured upon the governor body, a flexible shaft secured at one end to the said gear 105 stem, and gearing connecting the opposite end of the flexible shaft with one of the axles of the train whereby to transmit rotation thereof to the governor, said gearing including a worm secured upon the axle, a worm wheel in engagement with the worm, and a shaft upon which the worm wheel is 110 mounted, connected to the respective end of the flexible shaft.

3. In an automatic speed regulating device for trains, the combination with a train pipe having a vent, of a valve casing in communication with the vent of the train pipe and having an opening, a valve controlling the opening, a stem upon which the valve is secured having a portion extending within the valve casing and provided therein with an adjustable stop, a controlling spring between said stop and a portion of the valve casing to normally hold the valve in seated 115 120 125 130

position, a head having a limited movement with respect to the outer end of the valve stem, a spring controlling relative movement of the said head and the valve stem, a governor including a rod rotatably engaged with the said head, and gearing connections between the said governor and a wheel axle of the train.

4. In an automatic speed regulating device for trains, the combination with a train pipe having a vent, of a valve casing in communication with the vent of the train pipe and having an opening, a valve controlling the opening, a stem upon which the valve is secured having a portion extending within the valve casing and provided therein with an adjustable stop, a controlling spring between said stop and a portion of the valve casing to normally hold the valve in seated position, a head having a limited movement with respect to the outer end of the valve stem, a spring controlling relative movement of the said head and the valve stem, a governor including a rod rotatably engaged with the said head, and gearing connections between the said governor and a wheel axle of the train, said connections including a sectional worm secured to the axle of the train, a worm wheel in engagement with the worm, and a flexible shaft connecting the worm wheel with the governor.

5. In an automatic speed regulator for

trains, the combination with a train pipe having a vent, of a spring controlled valve normally seated to close the vent and having a projecting threaded stem, a plug threaded upon the said stem and adjustable thereon, a head having a limited movement with respect to the plug, a spring between the said plug and the said head, a governor including a governor rod one end of which is rotatably seated in the head, and gearing connections between the governor and a wheel axle of the train.

6. In a speed regulator for trains, the combination with a train pipe having a vent, of a valve, a spring normally holding the valve in seated position to close the vent, a governor, connections between the governor and the valve, including rods having adjacent ends, and a manually shiftable spring controlled member joining said rod ends, and permitting relative rotation thereof, whereby to open the valve against the tension of the spring thereof, and gearing connections between the governor and a wheel axle of the train, whereby to drive the governor at a speed proportionate to that of the train, all for the purpose described.

LELAND E. GLENN.
